ALVAH C. ROEBUCK, OF WOODSTOCK, ILLINOIS, ASSIGNEE TO WOODSTOCK TYPEWRITER COMPANY, OF WOODSTOCK, ILLINOIS, A CORPORATION OF ILLINOIS.

TYPE-WRITER PAPER-FINGER.

1,282,951.

Specification of Letters Patent. Patented Oct. 29, 1918.

Application filed May 21, 1915. Serial No. 29,458.

To all whom it may concern:

Be it known that I, ALVAH C. ROEBUCK, a citizen of the United States, residing at Woodstock, in the county of McHenry and State of Illinois, have invented certain new and useful Improvements in Type-Writer Paper-Fingers, of which the following is a specification.

This invention relates to typewriters and 10 more particularly to paper fingers of the type generally known as upwardly extending paper fingers. The principal object of the invention is to provide a simple construction of the type described in which the 15 paper finger is rigidly but yieldingly supported by the scale bar so that the upper end of the finger presses yieldingly against the platen.

Another object of the invention is to make 20 a paper finger of this class which is simple in construction and economical to manufacture and which is effective and efficient in operation.

Other objects of the invention will appear 25 hereinafter.

In the drawings, Figure 1 is a view in elevation of a paper finger applied to the shiftable carriage of a typewriter and constructed in accordance with the principles 30 of this invention; Fig. 2 is a sectional view taken on the line 2—2 of Fig. 1; and Fig. 3 is a detail view showing the connection of the scale bar with the typewriter carriage.

In some typewriter constructions the 35 paper fingers are supported from above and extend downwardly over the platen engaging the upper side of the paper on the platen or to hold the paper on the platen above the printing point. The present construction relates to a paper finger which is supported below or in front of the platen thereby providing means for rigidly and securely holding the paper finger as the paper finger extends upwardly with the 40 roller at the upper end to bear yieldingly downward on the paper thereby securing more uniform pressure and holding the paper more firmly against the platen.

In the drawings the numeral 1 designates 45 generally the frame or sub-carriage of a typewriter in which a platen 2 is rotatably mounted, the end pieces of the frame 1 being secured together by means of bars 4 and 5 and by means of a scale bar 6 located 50 at the front of the frame slightly below the axis of the platen 2. To this scale bar 6

is secured a graduated scale 7 and the upper and lower front edges of the scale bar are provided with longitudinally extending grooves or recesses 8. The scale bar 6 is 60 secured to the end of the frame 1 and held against rotation with respect thereto in any desired manner, as for example by providing the inside of the end pieces with a recess 9 and inserting a screw 10 through the end piece into a threaded recess 11 at the end of the scale bar, the recess 9 preventing the bar from rotating and the screw 10 holding the bar in position.

The paper finger proper comprises a single piece of material designated generally by the reference numeral 12 with slotted portions forming an intermediate spring finger 13. At the upper end the spring finger is formed with a finger-hold portion 14 and with ears 15 bent outwardly forming a bearing for a roller 16. The upper end of the paper finger conforms generally to the curvature of the platen 2 and the roller 16 bears against the platen adjacent 75 the upper end of the paper finger. At its lower end the paper finger is formed with a straight portion 17 which goes behind the scale bar 6 and at the upper and lower end of the portion 17 are the forward projecting angular portions 18 and 19 which are adapted to engage the longitudinal front grooves 8 on the scale bar. At the lower end of the spring 13 which is formed integral with the finger is a projection 20 which 80 engages the rear of the bar 6 and yieldingly holds the spring finger in contact with the bar so that the angular portions 18 and 19 bear yieldingly against the bar 6 thereby holding the spring finger in any position at 85 which it may be set along the bar. The spring finger is placed on the bar before the bar is fastened to the frame 1 and may be slipped along the bar by simply springing the outer end of the finger away from the platen which will relieve the roller 16 from its engagement with the platen and will allow the finger to be moved freely along the bar to any position desired. It 90 will be observed that the portion 17 of the finger at the rear side of the bar 6 stands away from the bar and is held in position by the projection 20 of the spring proper. The introduction of paper between the platen and the spring finger will press the 95 top part of the paper finger away from the platen, or, when the operator wishes to ad-

100

just the paper finger at different positions on the scale the top part of the paper finger is pulled toward the operator to relieve it from pressure on the paper whereupon the finger is then slidable endwise upon the bar 6. There being space between the body of the finger and the top part of the scale bar permits of the finger being pulled toward the operator a considerable distance, in which case the angle forms a loop which moves forward at the same time. The paper finger being formed with a spring integral therewith is very simple in construction and is therefore economical in manufacture. It is easy to adjust or remove the paper finger and there is nothing about it to get out of order. Being located at the front of the machine and on the scale bar the paper finger can be set very quickly at any desired position along the scale.

Of course it is obvious that instead of making the paper finger and tongue integrally of a single piece of material, a spring tongue might be riveted or otherwise secured to the paper finger and accomplish the same result. Although others may make various changes in the construction without departing from the spirit and scope of the invention it is preferable to make the device of a single piece of material as described.

I claim:

1. In a typewriter, the combination with a bar having a groove at its upper and lower edges on one side thereof, and a paper finger slidable thereon with a portion on the other side of the bar having hooks extending therefrom over the edges of the bar and engaging in the grooves.

2. In a typewriter, the combination with a bar having a groove at its upper and lower edges on the front side thereof with longitudinal graduations between the grooves, and a slidable paper finger having hooks extending over the upper and lower edges from the rear of the bar and resting in the grooves so as to offer no obstruction to said graduations.

3. In a typewriter, the combination with a bar having a groove at its upper and lower edges on one side thereof, a paper finger slidable thereon with a portion on the other

side of the bar having hooks extending therefrom over the edges of the bar and engaging in the grooves, and means for pressing the hooks yieldingly into the grooves.

4. In a typewriter, the combination with a graduated bar having grooves in the front face at the upper and lower edges thereof, of a paper finger slidable thereon having hooks extending over the upper and lower edges from the rear of the bar and resting in the grooves so that they offer no obstruction to the graduations, and a spring tongue bearing against the back of the bar for pressing the hooks yieldingly into engagement with their respective grooves.

5. In a typewriter, the combination with a platen, of a scale bar located below and in front of it adjacent the platen having longitudinal grooves on its forward edges, and a paper finger having forward angular extensions to engage the grooves from the rear thereof, and a spring tongue formed integral with the paper finger to hold the angular extensions yieldingly in the grooves and to hold the paper finger yieldingly against the platen.

6. In a typewriter, the combination with a platen, of a scale bar in front of but below the platen having longitudinal grooves at the upper and lower front edges, a graduated scale secured to the front of the bar and a paper finger constructed of a single piece of material with angular portions extending from the back of the bar to engage the front grooves thereof, the top angular portion permitting an oscillation of the finger with respect to the bar, the finger having a spring formed integral therewith, the free extremity of which engages the rear of the said bar and tends to hold the angular portions of the finger in their respective grooves and to hold the finger against the platen.

In testimony whereof I have signed my name to this specification, in the presence of two subscribing witnesses, on this 12th day of May A. D. 1915

ALVAH C. ROEBUCK.
